Inventor:

Leopold S. Samuel,
By Draxer & Co., Atty's.

UNITED STATES PATENT OFFICE.

LEOPOLD S. SAMUEL, OF NEWARK, NEW JERSEY.

CARD FOR BOOK-MARKS AND FOR ADVERTISING MEDIUMS.

SPECIFICATION forming part of Letters Patent No. 289,566, dated December 4, 1883.

Application filed June 25, 1883. (Model.)

To all whom it may concern:

Be it known that I, LEOPOLD S. SAMUEL, a citizen of the United States, residing at Newark, in the county of Essex and State of New Jersey, have invented certain new and useful Improvements in Cards for Book-Marks and for Advertising Mediums; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to provide a novelty acceptable to young people and adapted to meet the wants of advertisers; and it consists in the arrangements and combinations of parts, substantially as will be herein- 20 after set forth, and finally embodied in the claims.

The accompanying drawing indicates a plan of an advertising-card or book-mark, A being a card having a suitable amount of space 25 on it for printed matter, such as an advertisement or a motto, b b. Said card is perforated, as at c, and to it is attached, by an eyelet, d, or other fastener, arms e, adapted to revolve on said eyelet, and carrying disks f, of 30 glass, gelatine, or other colored and transparent substance. By revolving the arms the disks may be alternately or together brought over the perforation or perforations, so that on looking through the glass or transparent 35 material objects will be given the color of the said transparent matter, as will be understood. By combining two or more different colors secondary colors may be produced, in almost endless variety. The colors may be attached to the card and be adapted to project 40 over the edges thereof, and the perforation c be dispensed with, without departing from the spirit of my invention. When gelatine is used, I prefer to cover the same with mica to prevent 45 the hand from marring the surface, and thus reducing the transparency of the same.

To increase the value of the device in the 50 childish mind, so that the same will be retained longer and the value of the device as an advertising medium be increased, I provide

a background, g, of some contrasting color, and with or without a design imprinted thereon, and also lettered papers h, which parts g h are suitably gummed on their reverse sides, and thus adapted to be secured to the card. 55 From a collection of such parts g h the child may select the letters of his name, or make other selection, as he may desire, and secure the same to the card A.

Having thus described my invention, what I 60 claim as my invention is—

1. An advertising-card, A, provided with colored transparent and adjustable parts e, substantially as and for the purposes set forth and shown. 65

2. In combination, the card A and pivoted portions of transparent colored matter, substantially as set forth.

3. In combination, the card-board A, having a perforation therein, and pivoted arms 70 provided with differently-colored transparent portions f, substantially as and for the purposes set forth and shown.

4. In combination, a card provided with imprinted matter and pivoted arms having differently-colored transparent matter thereon. 75

5. An advertising-card having parts g and h secured thereto, and having a perforation, c, therein and pivoted transparent portion 80 thereon, as set forth.

6. In combination, the advertising-card having an imprint impressed thereon, and a background, g, and lettered portions h, gummed, glued, cemented, or otherwise secured to said card A by an adhesive substance, as herein 85 set forth.

7. In combination, the parts g h, secured by an adhesive substance to the card A, and said card A provided with a transparent and colored substance, to allow objects to be seen 90 therethrough, as herein set forth, said parts being arranged and operating for the purposes stated.

In testimony that I claim the foregoing I have hereunto set my hand this 15th day of 95 June, 1883.

LEOPOLD S. SAMUEL.
